UNITED STATES PATENT OFFICE.

FREDERICK C. HOLTZ, OF SPRINGFIELD, ILLINOIS, ASSIGNOR TO SANGAMO ELECTRIC COMPANY, OF SPRINGFIELD, ILLINOIS, A CORPORATION OF ILLINOIS.

CLOCK.

Application filed November 15, 1924. Serial No. 750,201.

My invention relates to clocks, and has particularly to do with the driving mechanism by which the time train of the clock is actuated. The primary object of my invention is to provide a clock or similar mechanism with a low power electric motor drive designed to obtain a maximum of simplicity in construction, whereby liability to derangement is reduced to a minimum, and 10 of such character that while the highly developed construction of a modern clock movement is retained to a large extent, it is rendered possible with but slight alteration to drive the same electrically whereby it 15 will require but little or no attention for long periods of time. A further object is to so design the mechanism that it will be compact; that a constant driving torque will be exerted, thereby greatly improving 20 the time-keeping qualities of the clock, and that all electrical contact devices will be eliminated and the electrical energy consumption be reduced to a minimum. I accomplish these objects as illustrated in the 25 drawings and as hereinafter described. What I regard as new is set forth in the claims.

In the accompanying drawings,—

Fig. 1 is a top or plan view of my improved clock, the case being omitted;

Fig. 2 is a side view, partly in vertical section on line 2-2 of Fig. 1;

Fig. 3 is a modified perspective view illustrating the relative arrangement of the 35 clock movement and the driving mechanism therefor, some parts being omitted for the sake of clearness;

Fig. 4 is a side view of the rotor element of the motor by which the main spring of the 40 clock is maintained under uniform tension, some parts being in section; and

Fig. 5 is an enlarged view of the spring barrel, the shaft on which said barrel is mounted being shown in section.

Referring to the drawings,—6 indicates 45 generally a clock movement of any suitable description, and 7 the drive staff thereof, by the rotation of which the torque necessary to keep the balance staff or pendulum in a 50 constant state of oscillation is supplied. Said staff is connected with the time train of the clock in any suitable way and, as best shown in Fig. 3, carries at its outer end a pinion 8 through which said staff is driven, 55 as will be hereinafter described. The clock

movement 6 is mounted between pillar plates 9, 10, as shown in Fig. 2, and is provided with the usual balance wheel 11, or equivalent device, and with a regulator 12. Extending over the pillar plate 9 is a dial plate 60 13 over which move the usual hour and minute hands 14, 15.

For driving the time train of the clock I provide a small induction motor, the stator of which comprises a single phase bipolar 65 laminated field magnet, indicated as a whole by the reference numeral 16, on which is mounted a coil 17 which constitutes the primary winding of the motor and is to be connected through its terminals 17^a, 17^b to 70 a source of supply of alternating current. The poles 18, 19 of the field magnet 16 have their opposite faces curved so that a cylindrical opening is provided between them in which is rotatably mounted the 75 armature or rotor 20 of the motor. Said rotor comprises a magnetic core member made up of a plurality of laminations 21, and a squirrel cage winding thereon consisting of bars 22 and end plates 23, 24, 80 which plates serve as end rings for the squirrel cage. The squirrel cage is preferably made of copper, and as best shown in Fig. 4 the bars 22 are obliquely disposed, the latter arrangement being employed to give uniform starting torque and thereby avoid a pulsating effect on the balance wheel spring. The ends of the bars 22 are preferably upset 85 after the parts of the rotor are assembled, as illustrated in Fig. 4, so that they serve to 90 securely hold the laminations together. While I prefer to use a laminated rotor, it is not essential that it be laminated, as a solid structure for many purposes will function equally well.

The rotor is mounted on a suitable shaft 95 to rotate therewith, said shaft being provided with a worm 26, preferably cut directly on said shaft, and with pivot pins 27, 28 at its opposite ends, by means of which 100 it may be rotatably supported in the manner hereinafter described.

As best shown in Figs. 1 and 3, the field magnet poles 18, 19 are provided with shading coils 29, 30 mounted on the pole tips in 105 the manner well known to those familiar with the art, which shading coils serve to change the pulsating flux of the field into a so-called shifting or substantially rotating magnetic field in the cylindrical space be- 110

tween the opposite poles of the field magnet. As best shown in Figs. 1 and 3, the field magnet 16 is mounted between two inverted U-shaped yokes 31, 32, the intermediate portions of which are bent outwardly to accommodate the shading coils 29, 30. In the intermediate portion of the yoke 31 is mounted a bearing plug 33 fitted in a threaded opening so that it may be adjusted endwise. Said plug is provided at its inner end with a socket to receive the pivot pin 28 of the rotor shaft 25, as best shown in Fig. 2. A lock nut 34 screwed upon the inner end of said bearing plug holds it securely in its different positions of adjustment. As shown in Fig. 2, the intermediate portion of the yoke 32 is provided with an opening 35 large enough to permit of the free passage therethrough of the armature shaft 25 and worm 26, and the pivot pin 27 of the rotor shaft 25 is fitted in a suitable bearing in a bearing plug 36 screwed into a threaded opening in a U-shaped bracket 37 that is secured by screws 38 to the yokes 31, 32 and lies between the field magnet and the pillar plate 10. By this construction the rotor shaft 25 is securely mounted and held so that it cannot get out of place, and the rotor is held in proper relation to the poles of the field magnet. A lock nut 36' is screwed on the inner end of the bearing plug 36 to secure it in its different positions of adjustment. At opposite sides of one end of the bracket 37 are provided wings 39, 40, the wing 39 being best shown in Fig. 1 and the wing 40 in Fig. 2. These wings are bent over approximately at right angles to the part of the bracket 37 with which they are connected and are parallel with each other. Their purpose is to support a shaft 41, best shown in Fig. 3, and to this end they are provided with suitable bearings in which said shaft is mounted. As shown in Fig. 3, the lower end of the shaft 41 is fitted in a bearing in the wing 40, and as indicated by dotted lines in Fig. 1 the opposite end of said shaft extends through a suitable bearing in the wing 39. Above said wing the shaft 41 is provided with a worm wheel 42 that meshes with and is driven by the worm 26 on the rotor shaft 25, as shown in Figs. 1 and 3. The shaft 41 also carries a worm 43 that meshes with and drives a worm wheel 44 carried by a drive shaft 45 mounted at one end in a suitable bearing in an arm 46 carried by the intermediate portion of the bracket 37, and at the other end journaled in a bearing in a plate 47 secured to the intermediate portion of the yoke 32, preferably by rivets 48. The arm 46 and plate 47 hold the shaft 45 securely in place, and as they constitute a part of a rigid frame which includes the yokes 31, 32, which in turn are firmly secured to the field magnet, it will be seen that the field magnet, together with the driving connections supported by

such frame, may be handled as a unit. This frame is firmly secured to the pillar plate 10 by a bracket 49 which is attached to said pillar plate in any suitable way, and is provided with a lug 50 adapted to fit over one of the out-turned ends 51 of the brackets 37 so that it may be secured thereto and to the field magnet by one of the screws 38, as best shown in Fig. 1.

At its inner end the shaft 45 has loosely mounted upon it a spring barrel 52 adapted to receive a main spring 53, the outer end of which is secured to said barrel, as shown at 54 in Fig. 5. The inner convolution of said spring is secured to the shaft 45 in any suitable way, as shown at 55 in Fig. 5. The arrangement is such that when the motor is in operation the shaft 45 will be rotated in a counter-clockwise direction as viewed in Fig. 5, thereby winding up the spring 53, assuming that the spring barrel 52 is held so that it cannot rotate in the same direction with the shaft 45. The spring barrel 52 is provided at its periphery with a gear 56 that meshes with the pinion 8, as shown in Fig. 3, the arrangement being such that rotation of the spring barrel under the action of the main spring 53 will rotate the pinion 8 in the proper direction to drive the time train.

From the foregoing description it will be apparent that the main spring 53 may be wound up by the operation of the motor, and that speed reducing gearing is provided between the rotor shaft of the motor and the shaft 45 by which the spring is wound. The object of this speed reducing gearing is to accommodate the speed of unwind of the spring barrel 52 to the speed of the induction motor, whose winding 17 is connected to any suitable source of alternating current supply, so that the motor will keep the spring 53 wound to a certain fixed tension, thus providing a constant torque in driving the clock mechanism. Any slight variation in the speed of the motor merely increases or decreases slightly the tension of the spring. Should the motor stop entirely, the barrel 52 continues to rotate until the spring 53 is unwound, as will occur should the electric power supply for any reason be disconnected. It is intended that the reserve power in the spring 53 shall be sufficient to keep the clock running for several hours without the aid of the motor, and this, in most instances, will bridge over any discontinuities in the electric power supply, thus enabling the clock to run almost indefinitely after being connected to a source of supply.

While I have described my invention as operated from a small alternating current motor, it will be quite evident to those skilled in the art that a small direct current motor operating under similar principles would fall within the scope of my invention.

What I claim as my invention and desire to secure by Letters Patent, is—

1. In an electric driving device for clocks, the combination of an electric motor having an extending motor shaft, a U-shaped bracket projecting from said motor and having a bearing at its end for receiving the extending end of said motor shaft, a worm on said motor shaft, two spaced wings projecting from one side of said bracket, a second shaft journaled in said wings, a worm wheel on said second shaft meshing with the worm on said motor shaft, a worm on said second shaft, a third shaft extending substantially parallel to said motor shaft and journaled at one end in said bracket, and a worm wheel on said third shaft meshing with the worm on said second shaft, said third shaft being adapted to transmit a drive to the clock. 15
2. In a winding device for spring motors, the combination of an electric motor having an extending motor shaft, a U-shaped bracket secured to said motor and having a bearing at its outer end for receiving the extending end of said motor shaft, a worm on said motor shaft, two spaced wings projecting inwardly from one side of said bracket, a second shaft journaled in said wings, a worm wheel on said second shaft meshing with the worm on said motor shaft, a worm on said second shaft, a third shaft extending at an angle to said second shaft, bearing means for said third shaft carried by said bracket, and a worm wheel on said third shaft meshing with the worm on said second shaft, said third shaft being adapted to transmit a slow speed winding rotation to the spring motor. 35
3. In an electric driving device for clocks, the combination of an electric motor having an extending motor shaft, a yoke secured to said motor, a U-shaped bracket extending outwardly from one side of said motor and having a bearing at its end for receiving the extending end of said motor shaft, a worm on said motor shaft, two spaced wings projecting inwardly from one side of said bracket, a second shaft journaled in said wings, a worm wheel on said second shaft meshing with the worm on said motor shaft, a worm on said second shaft, an arm carried by said yoke and having a bearing therein alined with a bearing in said bracket, a third shaft journaled in said bearings, and 50 a worm wheel on said third shaft meshing with the worm on said second shaft, said
- third shaft being adapted to transmit a slow speed drive to the clock.
4. In a winding device for spring motors, the combination of an alternating current induction motor comprising a laterally extending rotor shaft, a yoke at one side of said motor, a U-shaped bracket secured to said motor and extending from the other side thereof, bearing plugs screwing into threaded openings in said yoke and said bracket and receiving the ends of said rotor shaft, a worm on said rotor shaft, a pair of wings bent inwardly from one of the side arm portions of said bracket, a second shaft journaled in said wings, a worm wheel on said second shaft meshing with the worm on said rotor shaft, a worm on said second shaft, a bearing arm carried by the outer end of said bracket, a cooperating bearing plate carried by said motor, a third shaft journaled in said bearing arm and bearing plate, and a worm wheel on said third shaft meshing with the worm on said second shaft, said third shaft being adapted for operative connection with the spring motor. 65
5. The combination with clock mechanism comprising pillar plates, a time train mounted between said pillar plates, a drive staff connected therewith, and a main spring having a driving connection with said drive staff, of an electrically operated winding device for said main spring comprising an induction motor, a frame member secured to one of said pillar plates and supporting said induction motor directly in rear of said pillar plates, said induction motor comprising a rotor shaft extending forwardly towards said clock mechanism, a bearing bracket extending from said motor toward said clock mechanism and affording a bearing support for the end of said rotor shaft, a worm on said rotor shaft, a second shaft extending at an angle to said rotor shaft, bearing means for said second shaft carried by said bearing bracket, a worm wheel on said second shaft meshing with the worm on said rotor shaft, a worm on said second shaft, a third shaft extending substantially parallel to said rotor shaft and journaled in said bearing bracket, and a worm wheel on said third shaft meshing with the worm on said second shaft, said third shaft being adapted to transmit a slow speed winding rotation to said main spring. 75
